UNITED STATES PATENT OFFICE.

JOSEPH J. BURNS, OF TAMPA, FLORIDA, ASSIGNOR OF ONE-FOURTH TO FRANCES E. BURNS, OF TAMPA, FLORIDA.

METALLIC STUDDING.

1,413,828.

Specification of Letters Patent. Patented Apr. 25, 1922.

Application filed August 17, 1921. Serial No. 493,062.

To all whom it may concern:

Be it known that I, JOSEPH J. BURNS, a citizen of the United States, residing at Tampa, in the county of Hillsborough and 5 State of Florida, have invented new and useful Improvements in Metallic Studding, of which the following is a specification.

This invention relates to metallic partition studding, and its object is to provide 10 a novel and improved building element of this kind by the use of which a double-walled or hollow partition may be readily formed, and a structure is produced which is strong and durable.

15 The invention also has for its object to provide a studding which can be combined in various ways to support a number of partitions or walls arranged in different ways as will be pointed out in the detailed description appearing hereinafter.

The invention also has for its object to provide a novel and improved anchoring means for the studding.

In order that the invention may be better understood, reference is had to the accompanying drawings, forming a part of this specification, in which;

Figure 1 is a perspective view of a studding unit constructed in accordance with 30 the present invention; Figs. 2 and 3 are perspective views showing different arrangements of the studding; Fig. 4 is a plan view of a fragment of a wall or partition showing how the studding unit of Fig. 1 is used; 35 Figs. 5 and 6 are plan views showing how the studding units of Figs. 2 and 3 are used; Fig. 7 is a vertical section on the line 7—7 of Fig. 4, and Fig. 8 is a perspective view of an anchoring device.

40 Referring specifically to the drawing, and more particularly to Fig. 1, the studding unit here shown consists of three sheet metal plates, 10, 11 and 12, which are riveted or otherwise connected in face-to-face relation, 45 as shown at 13, to form a rigid web member. The outside plate 10 has out-turned lateral flanges 10^a at its ends and extending throughout its entire length, the other outside plate 12 is similarly flanged, as shown 50 at 12^a. The two outside plates 10 and 12 are therefore of channeled cross-section, the channels being presented outwardly in opposite directions. The width of the intermediate plate 11 is greater than that of the 55 outside plates 10 and 12 and hence it pro-

jects from both of the vertical ends of the latter. At the vertical ends of the plate 11 are out-turned laterally projecting tongues 11^a which extend alternately in opposite directions, one tongue extending from one side, and the next tongue from the opposite side. The tongues 11^a are integral with the plate and they can be readily produced by making horizontal slits in the plate inwardly from the vertical edges thereof, and then bending the material between the slits alternately in opposite directions.

It will be noted in Fig. 4 that the tongues 11^a on one side of the plate 11 are opposite the flanges 10^a of the plate 10, and the 70 tongues 11^a on the other side of plate 11 are opposite the flanges 12^a of plate 12. This arrangement produces at each vertical end of the studding unit two channels extending from the top to the bottom of the unit and 75 facing in opposite directions. These channels support the slabs or other units 14 employed in the construction of the wall or partition. As shown in Fig. 4, the wall or 80 partition is hollow and the web portions of the studding units seat transversely between the wall sections, and the vertical ends of the slabs 14 seat in the oppositely facing vertical channels at the ends of the 85 web. Each studding unit therefore supports the adjacent ends of four slabs 14. A studding unit as hereinbefore described can also be used at the corner of the structure shown in Fig. 4 by bending the flanges 10^a and 12^a, and the tongues 11^a to correspond to the 90 angle here made by the adjoining slabs. The bends can be made at any angle to correspond to the angle of the walls at the 95 corner.

The studding is held in place by anchoring strips 15 which are nailed or otherwise fastened to the floor and the ceiling. These strips seat on the top and bottom edges of the web portions of the studding units, and they have longitudinal medial ribs 15^a which fit in grooves in the top and bottom edges of the studding webs, as shown in Fig. 7. It will be understood that the anchoring strips 15 extend throughout the entire length of the wall for engagement with all 100 the studding units, and as the latter are locked to the strips by the groove and ribs, they, as well as the slabs 14 forming the wall sections are firmly anchored in place.

Fig. 2 shows a three-way studding unit 110

designed for holding the adjacent ends of six slabs arranged as shown in Fig. 5 to form two hollow partitions or walls extending at right angles to each other. Two units 5 similar to the first described unit are employed and coupled so as to extend at right angles to each other. One of the units is left in the same shape as the first described unit, and the other unit has its flanges 10^a 10 on one side of the web bent around back of the outer tongues 11^a at one end of the first mentioned unit, as shown at 10^b, whereby the two units are coupled together. The flanges 10 and 12^a and the tongues 11^a of 15 the first mentioned unit support four slabs 14 as before, and the flanges 12^a and the tongues 11^a on the outer side of the web of the other unit support two slabs of the adjoining wall as clearly shown in Fig. 5, 20 the tongues 11^a being all bent in the same direction instead of in alternate opposite directions as in the first-described unit.

Fig. 3 illustrates a four-way studding unit 25 designed for holding the adjacent ends of eight slabs 14 arranged to form three walls or partitions. This unit is made up of three of the first-described or single units joined and supporting the slabs in the same manner as the three-way unit shown in Figs. 2 30 and 5.

The studding is simple and inexpensive, and it can be easily put up, and by its use the partition or wall slabs or similar elements are securely held in place. The preferred embodiments of the invention have 35 been illustrated, but it will be understood that various other changes and modifications may be made without a departure from the spirit and scope of the invention, as 40 claimed hereinafter.

I claim:

1. A metallic studding unit comprising a medial plate and outside plates rigidly connected in face-to-face relation, the outer 45 plates having out-turned lateral flanges at their vertical ends, and the medial plate having its vertical end portions extending beyond the corresponding end portions of the outer plates, and provided on opposite sides 50 with outstanding lateral tongues which are parallel to and spaced from the aforesaid flanges.

2. A metallic studding unit comprising a medial plate and outside plates rigidly connected in face - to - face relation, the outer plates having out-turned lateral flanges at their vertical ends, and the medial plate having its vertical end portions extending beyond the corresponding end portions of 55 the outer plates, and provided on opposite sides with outstanding lateral tongues which

are parallel to and spaced from the aforesaid flanges, to form channels extending from the top to the bottom of the plates.

3. A metallic studding unit comprising a 65 medial plate and outside plates rigidly connected in face-to-face relation, the outer plates having out-turned lateral flanges at their vertical ends, and the medial plate having its vertical end portions extending beyond 70 the corresponding end portions of the outer plates, and provided on opposite sides with outstanding lateral tongues which are parallel to and spaced from the aforesaid flanges, to form end channels on opposite 75 sides of the unit extending from the top to the bottom thereof and facing in opposite directions.

4. A metallic studding unit comprising a medial plate and outside plates rigidly connected in face-to-face relation, the outer plates having out-turned lateral flanges at their vertical ends, and the medial plate having its vertical end portions extending beyond the corresponding end portions of the 80 outer plates, and provided on opposite sides with outstanding lateral tongues which are parallel to and spaced from the aforesaid flanges, and top and bottom anchoring strips for the aforesaid unit, said strips having 85 ribs, and the unit having grooves in its top and bottom edges in which the ribs seat.

5. A metallic studding unit comprising a member having end channels on opposite sides extending from the top to the bottom 95 thereof and facing in opposite directions, and top and bottom anchoring strips for said member, said strips having ribs and the member having grooves in its top and bottom edges in which the ribs seat. 100

6. A metallic studding unit comprising a member having pairs of outstanding lateral flanges at its vertical ends and on opposite sides, and a second member extending transversely of said member at one end thereof, 105 said second member having end channels on its outer side extending from the top to the bottom thereof.

7. A metallic studding unit comprising a member having pairs of outstanding lateral flanges at its vertical ends and on opposite sides, and a second member extending transversely of said member at one end thereof, 110 said second member having end channels on its outer side extending from the top to the bottom thereof, and the inner face of said second member having flanges which are interlocked with the outer ones of the flanges at one of the vertical ends of the first-mentioned member. 115

In testimony whereof I affix my signature.

JOSEPH J. BURNS.
